UNITED STATES PATENT OFFICE.

ELIHU THOMSON, OF SWAMPSCOTT, MASSACHUSETTS, ASSIGNOR TO
GENERAL ELECTRIC COMPANY, A CORPORATION OF NEW YORK.

DIAPHRAGM-ACTUATED MECHANISM.

No. 832,708.

Specification of Letters Patent.

Patented Oct. 9, 1906.

Application filed March 25, 1904. Serial No. 200,016.

To all whom it may concern:

Be it known that I, ELIHU THOMSON, a citizen of the United States, residing at Swampscott, in the county of Essex and State of Massachusetts, have invented certain new and useful Improvements in Diaphragm-Actuated Mechanisms, of which the following is a specification.

The object of the present invention is to provide a diaphragm-actuated mechanism for use in connection with valves, regulators, and other devices which is sensitive to small variations in pressure, has a wide range of movement, and is capable of withstanding high pressures without injury.

In carrying out my invention a relatively thin diaphragm is provided, which is preferably made of some tough spring metal, although other materials may be substituted therefor. The diaphragm may be made smooth or corrugated, depending upon the service for which it is intended and also upon the desired range of movement. The object in making the diaphragm thin is to make it sensitive to small variations in pressure. Such a diaphragm, however, as previously constructed is open to the serious objection of weakness when used for anything except very low pressures, and frequent operation thereof usually causes the same to break, the action being much the same as that of a punch and die. I overcome this objection by reinforcing the diaphragm in a novel manner. Extending between a head or movable part attached to the center of the diaphragm or moved thereby and the surrounding wall of the casing are a plurality of radially-extending levers which reinforce the diaphragm at a number of points. The number of these levers can be varied as desired; but all things being equal the more there are the stronger will be the construction. The levers are arranged to engage the movable head and the stationary surrounding wall. At the points of engagement each lever may be advantageously provided with a well-rounded end, forming a bearing which acts in a manner similar to a ball-joint and permits the parts to roll or move slightly one on the other without binding or cramping.

It is impractical to have a great number of levers, owing to the fact that the central head or movable piece with which they engage is of small diameter as compared with

the diameter of the diaphragm itself. In order to permit the use of a small number of these levers, I provide means which rest on the diaphragm and extend between it and the levers, each of the said means preferably engaging with two or more levers. The most satisfactory arrangement which I have found for this purpose comprises a plurality of concentric rings or segments thereof which may be spaced apart or be in contact with each other. When spaced apart, it necessitates special spacing devices—such, for example, as notches in the levers. When the diaphragm is provided with concentric corrugations, the rings can rest in the depressions on one side or be held by notches in the levers at the other.

The head is attached to a valve, regulator, or other device to be actuated by the diaphragm, and said head may be located on either side of the diaphragm or extend through it. The diaphragm is moved in one direction by fluid under pressure, which pressure may be opposed by another fluid under pressure or by a spring or equivalent device. When the parts are properly assembled, the diaphragm will receive its motion, due to relative changes in pressure, on opposite sides thereof, and this motion is in turn transmitted to the levers either directly by the diaphragm engaging the levers or indirectly by acting on the concentric rings. As the diaphragm moves the levers will also move proportionately, the outer ends acting as the center of motion therefor. In this manner the strain is evenly distributed over the entire surface of the diaphragm and the danger due to breaking reduced to a minimum.

It is to be noted that owing to the arrangement of the rings and levers every part of the diaphragm is rendered effective—that is to say, there is no substantial area out of engagement with the ring. Hence the tendency of the diaphragm to bulge unevenly between the center and the edge is obviated. In this connection it must be borne in mind that any irregularity or unevenness of the diaphragm in a given position represents a loss in effective action. I regard the feature above referred to as being an important part of my invention.

In the accompanying drawings, which illustrate certain embodiments of my invention, Figure 1 is a vertical section of an automa-

ically-actuated valve. Fig. 2 is a cross-section taken on line 2 2 of Fig. 1. Fig. 3 is a perspective view of one of the rings for reinforcing the diaphragm. Fig. 4 is a perspective view of one of the levers for reinforcing the diaphragm. Fig. 5 is a partial sectional view showing a flat diaphragm. Fig. 6 is a partial sectional view taken on line 6 6 of Fig. 5. Fig. 7 is a perspective view of one of the levers used in the structure shown in Fig. 5, and Fig. 8 is a detail view showing certain of the parts enlarged.

Referring to Fig. 1, 1 represents a casing of any suitable construction which is provided with an inlet-port 2 and a discharge-port 3, the passage of fluid from one port to the other being controlled by an automatically-actuated valve 4. The casing is provided with a detachable cover 5, which engages a shoulder 20 formed thereon, and between the cover and the shoulder is located a corrugated diaphragm 6. The cover is provided with an internal shoulder 7, with which the outer ends of the radially-extending levers 8 engage. It is also provided with an external screw-thread arranged to receive the adjusting-nut 9. The cover is provided with a central opening which forms a guide for the cylindrical extension 10 on the head 11. The upper side of the head is rounded somewhat to receive the collar 12, on which the coil compression-spring 13 engages. The head is screw-threaded to receive the valve-stem 14, and the nut 9 is provided with a central opening which receives the upper end of the stem and acts as a guide therefor. By adjusting the vertical position of the nut the tension of the spring can be varied, and therefore the opposition to movement of the diaphragm. The under side of the head is provided with a hub-like projection which rests on the upper side of the diaphragm. Situated below the diaphragm and mounted on the valve-stem is a plate 15, which has a somewhat rounded upper surface where it engages with the diaphragm. The object in rounding this surface is to prevent it from cutting the diaphragm. The diaphragm is corrugated, and in the depressions thus formed are rings 16, which may be made in a single piece or segments, as desired. Situated above the rings are the radially-extending levers 8, which are provided with rounded ends 18, that engage with an internal shoulder 7, formed on the cover, and the external shoulder 19, formed on the head. The under side of some or all of the levers may be provided with notches 20, which serve to center the rings. The chamber above the diaphragm may be partially filled with fluid 60 for the purpose of checking the sudden movements of the diaphragm after the manner of a dash-pot.

In Fig. 2 the relation of the levers 8 to each other and to the concentric rings is clearly shown.

In Fig. 5 the diaphragm 6 is made flat instead of corrugated, and the rings 16 instead of being spaced apart are in more or less intimate frictional engagement with each other. Situated above the rings are levers 21, which instead of being notched on their under side are perfectly plain, but are provided with shoulders 22 at the ends. These shoulders serve to prevent the rings as a whole from assuming a non-concentric relation with respect to the valve-stem 14. In order to reinforce the diaphragm, the portion of the cover 23 just below the curved outer end of the lever is extended inwardly to a point in close proximity to the outer ring. The central portion of the diaphragm around the head and between it and the inner ring is reinforced by a nut 24.

In Fig. 8 is shown a slight modification, wherein the diaphragm is uncorrugated, and the head 25 is provided with a cylindrical projection 26, with which the inner ends of the levers engage. Situated below the head and forming an extension thereof is a part 27, having an enlargement 28 to reinforce the diaphragm at the central portion. The rings 29 are separated one from the other by a small space and are well rounded on their under side to prevent injury to the diaphragm 30. The outer ends of the levers 35 engage with an internal shoulder formed on the cover.

In accordance with the provisions of the patent statutes I have described the principle of operation of my invention, together with the apparatus which I now consider to represent the best embodiment thereof; but I desire to have it understood that the apparatus is only illustrative and that the invention can be carried out by other means.

What I claim as new, and desire to secure by Letters Patent of the United States, is—

1. An apparatus of the character described, comprising a diaphragm sensitive to pressure differences, a casing in which the diaphragm is arranged, and means for opposing the action of the diaphragm, in combination with a plurality of rings bearing against the diaphragm to reinforce the same, and means movable with the diaphragm for maintaining the rings in operative relation thereto.

2. An apparatus of the character described, comprising a diaphragm sensitive to pressure differences, a means for opposing the action of the diaphragm, and a surrounding casing in which the diaphragm is seated, in combination with one or more rings or segments thereof which engage the diaphragm, and radially-extending levers which engage the rings for sustaining the pressure to which the diaphragm is subjected.

3. An apparatus of the character described, comprising a diaphragm sensitive to pressure differences, a means for opposing

the action of the diaphragm, and a surrounding casing in which the diaphragm is seated, in combination with a plurality of rings which are seated on the diaphragm, means 5 for spacing the rings apart, and levers engaging the rings for sustaining the pressure on the diaphragms.

4. An apparatus of the character described, comprising a diaphragm sensitive to 10 pressure differences, a means for opposing the action of the diaphragm, and a surrounding casing in which the diaphragm is seated, in combination with a head which is provided

with an external shoulder adjacent to the diaphragm, a cover for the casing having an 15 internal shoulder, a plurality of concentric rings which are seated on the diaphragm, and radially-extending levers which rest upon the rings and engage the shoulders.

In witness whereof I have hereunto set my 20 hand this 22d day of March, 1904.

ELIHU THOMSON.
